UNITED STATES PATENT OFFICE.

JAMES W. MUSKETT, OF SCRANTON, PENNSYLVANIA.

PIPE-WRENCH.

SPECIFICATION forming part of Letters Patent No. 761,389, dated May 31, 1904.

Application filed August 14, 1903. Serial No. 169,468. (No model.)

To all whom it may concern:

Be it known that I, JAMES W. MUSKETT, a citizen of the United States, residing at Scranton, in the county of Lackawanna and State 5 of Pennsylvania, have invented new and useful Improvements in Pipe-Wrenches, of which the following is a specification.

My invention relates to pipe-wrenches.

The present invention relates to that general class of pipe-wrenches embodying a handle with a stationary jaw and a movable or adjustable jaw connected to the stationary jaw by links, and has for its object the provision of an improved and novel construction 15 of great strength, durability, and simplicity adapted for rapid and easy adjustment and having the jaws self-opening.

Having the foregoing and other not specifically-mentioned objects in view, the invention 20 embraces certain improved and novel arrangements and combinations of parts set forth in detail hereinafter and embodied in the appended claims.

In the accompanying drawings, Figure 1 is 25 a side elevation showing the jaws as opened by the springs to their fullest extent; Fig. 2, a similar view showing the adjustable jaw nearly closed on the rigid jaw; Fig. 3, a section on line *xx* of Fig. 1 looking toward the fixed jaw, and Fig. 4 a section on line *yy* of Fig. 1 looking toward the movable jaw.

The rigid or fixed jaw 1 is made integral 30 with a handle 2, which is provided with elongated concavities 3 on its opposite sides.

The adjustable or movable jaw 4 is located 35 between and pivoted by a pin 5 to two links 6 and 7, which in turn are pivoted to the opposite sides of the jaw 1 by a pin 8. The two jaws and the link are provided with teeth 9. 40 The lower end of the adjustable jaw 4 is provided with ears 10 and 11, which are adapted to embrace opposite sides of the handle and are turned into the concavities 3, so as to engage with the margin thereof.

45 Projecting from opposite sides of the jaw 1 are studs 12 and 13, which are split and securely receive leaf-springs 14 and 15, which

bear against the links 6 and 7. The tendency of these springs is to open the jaws.

On applying the wrench to a pipe and operating the handle the movable jaw 4 will be moved from the position shown in Fig. 1 in the direction of the position shown in Fig. 2, thereby securely grasping the pipe, and the greater the pressure on the handle the firmer will be 50 the grip of the jaws on the pipe.

Having thus described my invention, what I claim as new, and desire to secure by Letters Patent, is—

1. In a pipe-wrench, the combination with 60 a stationary jaw and operating-handle connected together, of a movable jaw having a portion thereof engaged with and guided by the handle, a link connecting the movable jaw with the stationary jaw, and a spring coöperating with the link to open the jaws.

2. In a pipe-wrench, the combination with 65 a stationary jaw and handle connected thereto, of a movable jaw having a portion thereof engaged with and guided by the handle, a link 70 connecting said jaws to permit relative movement thereof and a spring secured to said stationary jaw and bearing against said link.

3. In a pipe-wrench, the combination with 75 a stationary jaw and a handle for operating said jaw, of a movable jaw slidably engaged with said handle, a link pivotally connecting the two jaws, a stud on one of the jaws, and a leaf-spring connected to said stud and bearing against the link.

4. The herein-described pipe-wrench comprising a stationary jaw, a handle connected thereto, a movable jaw having a portion slidably engaged with the handle, links pivoted to said jaws, studs projecting from one of the 85 jaws, and leaf-springs secured to said studs and engaged with the links.

In testimony whereof I have signed my name to this specification in the presence of two subscribing witnesses.

JAMES W. MUSKETT.
